UNITED STATES PATENT OFFICE

FREDERICK W. STARK, OF MERIDEN, CONNECTICUT, ASSIGNOR TO INTERNATIONAL SILVER COMPANY, OF MERIDEN, CONNECTICUT, A CORPORATION OF NEW JERSEY

DESIGN FOR A DISH OR OTHER SIMILAR ARTICLE OF HOLLOW-WARE

Application filed April 1, 1932. Serial No. 43,352. Term of patent 14 years.

To all whom it may concern:

Be it known that I, FREDERICK W. STARK, a citizen of the United States, residing at Meriden, county of New Haven, State of Connecticut, have invented a new, original, and ornamental Design for a Dish or Other Similar Article of Hollow-Ware, of which the following is a specification, reference being had to the accompanying drawing, forming a part thereof:

Fig. 1 is a top plan view of a dish embodying my invention, it being understood that the ornamentation is continued around the entire circumference;

Fig. 2 is a side view thereof showing the border design also applied to the bottom;

Fig. 3 is a fragmentary view of the ornamental border only, on an enlarged scale,

for the purpose of bringing out the details of the design; and

Figs. 4 and 5 respectively show sectional views along the lines A—A and B—B of Fig. 3.

The ornamental border design is here shown as applied to a dish; but it is likewise applicable to hollow-ware generally such as tea sets, vegetable dishes, meat dishes; and the design may be applied to the rim or base of the dish alone, or to both the rim and the base.

I claim:

The ornamental design for a dish or other similar article of hollow-ware substantially as shown and described.

FREDERICK W. STARK.
